UNITED STATES PATENT OFFICE.

CLAUDE HENRY RATLIFF, OF PLATEAU, ALABAMA.

SWITCH-OPERATING MECHANISM.

1,210,838.

Specification of Letters Patent.

Patented Jan. 2, 1917.

Application filed April 19, 1916. Serial No. 92,240.

To all whom it may concern:

Be it known that I, CLAUDE H. RATLIFF, a citizen of the United States, residing at Plateau, in the county of Mobile and State of Alabama, have invented certain new and useful Improvements in Switch-Operating Mechanisms, of which the following is a specification, reference being had to the accompanying drawings.

This invention relates to mechanism for operating switches and particularly a mechanism for operating switches on street car or interurban lines.

The general object of the invention is the provision of a very simple switch point operating mechanism so arranged that it may be actuated by a motorman on a car operating in either direction so as to throw the switch and further so arranged that cars may pass through the switch, the switch point returning to its set position after the cars have passed through.

A further object of the invention is the provision of a very simple mechanism mounted upon the car which is adapted to positively engage with a switch operating wheel and rotate it.

Another object is to provide means which may be applied to ordinary switch points without change, whereby the switch points may be thrown by an approaching car.

Other objects will appear in the course of the following description.

The invention is illustrated in the accompanying drawings, in which,

Figure 1 is a top plan view of my switch operating mechanism; Fig. 2 is a section on the line 2—2 of Fig. 1; Fig. 3 is a plan view showing the manner in which a jointed shaft 40 20^a may be used in place of the shaft 20; Fig. 4 is a side elevation of the track section shown in Fig. 1; Fig. 5 is a cross section through the platform of a car and through the rails showing the switch operating mechanism; Fig. 6 is a sectional view of a slotted rail showing a modified manner of arranging the switch operating wheel; and Fig. 7 is a top plan view of the construction shown in Fig. 6.

Referring to these drawings, A designates a line of track, while B designates a branch track. The rail a carries the switch point 10 which, when thrown in one direction, permits the car to pass from or on to the branch track and which when thrown in the other direction, permits passage along the main

track. Attached to the switch point in any suitable manner, is an outwardly extending rod 11, this rod being preferably attached to the switch point by the eye bolt 12 so that the rod may have a slight pivotal movement. A switch operating bar 13 is provided, formed at one end with an angular extension 14, perforated for the passage of the rod 11. The rod 11 at one end is formed with a head 15 and distanced from this head is a collar 16 and disposed between the collar 16 and the angular portion 14 of the switch operating rod and between the switch operating rod and the head 15, are the coil springs 17, which have strength enough to resist ordinary compression, so that under normal circumstances, the rod 11 will move with the actuating rod 13. The actuating rod 13 at its outer end terminates in an eccentric sleeve or ring 18 operating within which is an eccentric 19. This eccentric is mounted upon a shaft 20 which extends longitudinally of the track and is mounted in suitable bearings 21.

The shaft 20 extends longitudinally of the track, as before stated, to a position any desired distance in advance of the switch point 10 and carries upon it a bevel gear wheel 22. Disposed beside the track and mounted in any suitable bearings, is a short shaft 23 which carries upon it a bevel gear wheel 24, which meshes with the bevel gear wheel 22. This bevel gear wheel 24 is provided with the radially projecting arms 25 which are illustrated as four in number. It will be noted that the gear wheel 24 has twice the diameter of the gear wheel 22 so that a quarter rotation of the gear wheel 24 will cause a one-half rotation of the shaft 20.

Mounted upon each platform of the car C is a lever 26. There may be one or more of these levers, as desired, and I have illustrated two in Fig. 5. Each lever is attached to a rock shaft 27 mounted in bearings on the platform, the lever passing up through a slot 28 in the platform. Depending from the rock shaft is the arm 26^a of the lever which at its lower end is laterally deflected and has its extremity angularly bent as at 29. Operatively supported on the lower end of the arm 26^a of the lever is a flanged wheel 30 adapted to run along the rail a while the deflected extremity 29 of the lever projects in a position to engage with one of the arms 25 of the gear wheel 24. As illustrated in Figs. 6 and 7, the rail 21 may be

longitudinally chambered and slotted, as at 31, and the wheel 24^a may be disposed in this chamber, its arms extending into the slot so that the deflected lower end of the lever may extend through this slot the wheel 24^a being so disposed that the arms 25 will operate in this slot. Thus the lower terminal end of the lever will be sure to engage one of the upwardly projecting arms 25 to rotate the wheel 24^a. It is to be understood, of course, that the arms 25 are so disposed and the parts are so adjusted that the arms will extend at an angle of about 45 degrees to the rail and so that when the terminal 15 end of the lever engages with these arms, they will rotate the wheel 24^a through a quarter revolution. Preferably a sector rack 32 is provided over which the lever operates, the lever being provided with a pawl 20 engaging with this rack so that the lever may be held in either its depressed or raised position. In one position of the lever, the terminal end of the lever and the wheel 30 will be raised completely from the track. 25 In another position of the lever, however, the wheel 30 will rest upon the track, while the terminal end 29 will project below the rail in position to engage one of the arms 25. Preferably, in order to secure a solid 30 bearing for the shaft 23 and the wheel 24, I provide a block 33 adapted to be disposed between the base and head of the rail and through which the shaft 23 passes and against which the wheel 24 operates. Preferably, also, the eccentric rod 13 operates over a wear plate 34.

It is to be understood that the eccentric has a diameter sufficient to cause the opening of the switch point 10 when the shaft is rotated one-half a revolution in one direction and close the switch point when the shaft is rotated the next one-half revolution in the same direction.

45 The operation of the device will be obvious from what has gone before.

When a car approaches the switch, (the car moving toward the point of the switch) the motorman if he desires to shift the switch will depress the lever so that it will 50 positively engage with one of the arms 25. This will rotate the bevel gear wheel 24 through a one-fourth revolution giving a one-half revolution to the shaft 20 and to the eccentric. If the switch point 10 be 55 closed against the main rail, then the rotation of the shaft 20 and eccentric will cause the switch point to open to the position shown in Fig. 1. Under these circumstances the car will be shifted on to the side track. If, however, the switch point be 60 open to the side track, and the car approaches desiring to pass along the main track, then a rotation of the gear wheel 24 will give a reverse movement of the switch 65 point. Of course, if the car does not desire

to approach the switch point, the motorman does not depress or dispose the lever in an operative position.

Inasmuch as the switch point is mounted for movement independent of the actuating rod 13, it is obvious that a car approaching on the branch line and desiring to pass on the main line, can do so, the car wheel simply pushing the point open and running through the point. If, on the other hand, 70 the car approaches the switch on the main line and the switch is open, then the flange of the wheel will not push the switch point closed and the car will move along and after it has passed the switch point, will again be 75 shifted to its open position. The eccentric sleeve or ring is made in two parts as usual, so that if the switch works too easily, the two sections of the eccentric sleeve or strap may be turned more tightly on the eccentric by 80 means of the bolts 19^a. It is also obvious that the gear wheel 24 can be readily adjusted upon the shaft 23 so as to secure a proper timing of the several parts. Preferably, on each platform, there will be two 85 levers 26 mounted upon the rock shaft 27 so that switches on either side of the track may be thrown. It is obvious, however, that the switch mechanism can be so arranged that a switch on one side of the track will 90 be thrown by a gear wheel 24 mounted on the opposite side of the track so that thus the gear wheels 24 may all be arranged on the same side of the track, even though the 95 switches be on opposite sides.

100 The operating mechanism of the switch is intended to be protected by a metallic housing, while the shaft 20 will preferably pass through a tubular housing 34. It is obvious that the particular character of the housing is no part of my present invention.

105 As illustrated in Fig. 3, the shaft 20 might be made up of sections 20^a having a universal joint connection with each other, each section operating in a suitable bearing 21^a 110 so that the shaft could shift around a curve and permit the positive operation of the switch point by a car passing around a curve. The operating mechanism illustrated in Fig. 3 is precisely the same as 115 that illustrated in Fig. 1, namely, a wheel 24^b provided with radiating arms and carrying a bevel gear 22^b meshing with the bevel gear wheel on the first shaft section.

120 What is claimed is:

1. The combination with a switch point, of a switch rod extending therefrom, a shaft extending longitudinally of the track, in advance of the switch point, an eccentric mounted on the shaft, a sleeve surrounding the eccentric, an eccentric bar extending from the sleeve, having loose connection with the switch rod, springs surrounding the switch rod and bearing against the eccentric bar and resisting independent move- 130

ment of the switch rod with relation to the bar, a bevel gear wheel carried upon the shaft, a bevel gear wheel disposed in a plane parallel to the track, and engaging the first named bevel gear wheel, and radially disposed arms projecting from the second bevel gear wheel and adapted to be engaged by switch operating mechanism on a car.

5 2. The combination with a track including a switch point, of a shaft extending longitudinally of the track, a rotatable member 10 on the shaft operatively engaging the switch point, whereby a half rotation of the shaft will oscillate the switch point from one operating position to another, a bevel gear

wheel on the shaft, a bevel gear wheel disposed in a plane parallel to the track and engaging the first named bevel gear wheel and having a diameter twice as great as that of the first named bevel gear wheel, and arms 20 extending radially from the second named gear wheel adapted to be engaged by an operating member on a car.

In testimony whereof I hereunto affix my signature in the presence of two witnesses. 25

CLAUDE HENRY RATLIFF.
